[57] **CLAIM**

The ornamental design for a vehicle roof rack, substantially as shown and described.

DESCRIPTION

FIG. 1 is a perspective view of a vehicle roof rack of my new design mounted on a vehicle with the roof removed, the vehicle being shown in broken line;

FIG. 2 is a perspective view of a vehicle roof rack of my new design mounted on a vehicle with the roof in place, the vehicle being shown in broken line;

FIG. 3 is a front view of the vehicle roof rack of FIGS. 1 and 2;

FIG. 4 is a rear view of the vehicle roof rack of FIGS. 1 and 2;

FIG. 5 is a first side view of the vehicle roof rack of FIGS. 1 and 2;

FIG. 6 is a second, opposite side view of the vehicle roof rack of FIGS. 1 and 2;

FIG. 7 is a top plan view of the vehicle roof rack of FIGS. 1 and 2; and,

FIG. 8 is a bottom plan view of the vehicle roof rack of FIGS. 1 and 2.

The broken line representation of a vehicle is environmental only and it forms no part of the claimed design.
